(57) **CLAIM**

The ornamental design for a reciprocating saw, as shown and described.

DESCRIPTION

FIG. 1 is a left side perspective view of the present new design for a reciprocating saw;

FIG. 2 is a left elevational view thereof;

FIG. 3 is a right elevational view thereof;

FIG. 4 is a top plan view thereof;

FIG. 5 is a bottom plan view thereof;

FIG. 6 is front elevational view thereof; and,

FIG. 7 is a rear elevational view thereof.

The broken lines showing various features of a reciprocating saw are for illustrative purposes only and form no part of the claimed design. Stippling has been applied to certain surfaces to represent differential surface treatment and this is considered to be a claimed feature of the ornamental design.
